To all whom it may concern:

Be it known that I, PAUL OTTO MUELLER, a citizen of the United States, and a resident of the city of New York, borough of Brooklyn, in the county of Kings and State of New York, have invented a new, original, and ornamental Design for an article of manufacture designated now as a Spool-Holder, reference being had to the accompanying drawing, forming a part of the same, wherein—

The figure represents a perspective view of my design in its entirety.

My design comprises the representation of a one legged soldier in the usual uniform of the United States Army, wearing an overseas hat and being supported by crutches that in turn support spools of thread and a pincushion.

What I claim and desire to secure by Letters Patent, is:
